UNITED STATES PATENT OFFICE

118,746

DESIGN FOR AN ASHTRAY

John F. Schylander, Chicago, Ill.

Application November 9, 1939, Serial No. 88,158

Term of patent 7 years

To all whom it may concern:

Be it known that I, John F. Schylander, a citizen of the United States, residing at Chicago, in the county of Cook and State of Illinois, have invented a new, original, and ornamental Design for an Ashtray, of which the following is a specification, reference being had to the accompanying drawing, forming a part thereof.

Referring to the drawing:

Fig. 1 is a perspective view of a tray embodying the present design; and

Fig. 2 is a side elevational view of the same.

I claim:

The ornamental design for an ashtray, as shown,

JOHN F. SCHYLANDER.
